ABSTRACT: Apparatus for operation in a system using TFL (through the flow line) tools, wherein it is desirable to direct the tool into one of a plurality of paths. To divert the tool, a rotatable member is provided which is capable of alining an inflow tube with one of a plurality of outflow tubes depending upon its rotated position. The flow of TFL fluid or gas is controlled by external valving which prevents any interconnection between the systems of each of the paths thus allowing the use of a simpler, less expensive diverter design.

TOOL DIVERTER FOR DIRECTING TFL TOOLS

BACKGROUND OF THE INVENTION

1. Field of the Invention

The present invention relates to a system including a tool diverter for guiding a TFL tool into one of a plurality of tubing outlets associated with a plurality of wells or well completions, and more particularly to a remotely actuatable tool diverter capable of utilization in an automated system for servicing a plurality of wells or well completions.

2. Description of Prior Art

In recent years the drilling of offshore wells have gained increasing prominence consonant with the desire to maintain and expand the country's gas and oil reserves. In order to effect maintenance and other operations on such wells wherein the wellhead assembly may be positioned on a considerable distance below the surface of the water, various methods have been developed. One of these methods utilizes so-called through the flow line (TFL) tools for performing a variety of functions such as scraping paraffin, setting plugs, etc. When combined with pistons, these TFL tools are pumped "down" into a well through the production line by pressurizing the production line above the tool. Later the tool is pumped "up" again by pressurizing the lower end of production line through a service line (sometimes called the TFL fluid line). Because these tools consist of a chain of parts, the conducting tubes and path directing diverters have to provide a straight through or a slightly curved passage which avoids abrupt changes of direction. The TFL system thus described is known and forms no part of the instant invention.

The purpose of a tool diverter is to channel TFL tools which are pumped from one station (above the water or in an underwater pressure vessel) to one of two or more tubing lines leading to two or more different wells or to different oil sands in one well.

Prior diverter designs have required either the services of a diver to descend to the diverter position and set it to the required setting or else they have required a special setting tool to be pumped down from the surface and returned. Such methods are not suitable where it is desired to effect periodic, automatic servicing of a plurality of wells or well completions. Further prior systems have required pressure tight joints between the moving and the fixed part of the diverter to contain the pressure inside the selected track only. This requirement, of course, increases the complexity and cost factors considerably.

SUMMARY OF THE INVENTION

According to the present invention, a simple, low cost, automatic TFL tool diverter is disclosed. A main diverter body with an inflow pipe connection is secured to a cover which contains a plurality of outflow pipes. The main diverter body contains a tapered bore with a cylindrical bore extending toward the inflow pipe. A plug-type deflector body, secured to a shaft, contains a groove running in extension of the portion of the deflector body. The shaft is rotated by either an electric or hydraulic motor or hydraulic cylinder acting via gears or gear and rack on shaft or other suitable mechanical means, thus rotating the deflector body and varying the path through the tool diverter. The actuation is susceptible of being controlled remotely and automatically, thus providing the capability of inclusion in a predetermined periodic maintenance system. Further, the diverter is utilized in a system wherein valves are placed in each line leading to the diverter. The flow of TFL fluid or gas is controlled by the valves which provides effective isolation between the systems of each of the wells or well completions thus eliminating the necessity for pressure tight joints between the moving and fixed parts of the diverter. The elimination of the requirement for pressure tight joints between the moving and fixed parts allows for considerable simplification in diverter design and construction.

OBJECTS

It is therefore an object of this invention to provide a novel TFL tool diverter.

It is a further object of the invention to provide a system for remotely directing TFL tools, pumped from the surface or from an underwater pressure vessel to one of two or more production lines coming from one of two or more formations of a multicompletion well or one of two or more wells.

It is still a further object of the present invention to provide a simple device which can be remotely actuated to guide a TFL tool into of two or more selected tubing outlets.

It is another of the present invention to provide a system including a tool diverter wherein the flow of TFL fluid or gas is completely controlled by valving external to the tool diverter thus preventing any interconnection between the systems of each of the well completions.

Still other objects, features and attendant advantages of the present invention will become apparent to those skilled in the art from a reading of the following detailed description of several embodiments constructed in accordance therewith taken in conjunction with the accompanying drawings and wherein:

25 BRIEF DESCRIPTION OF THE DRAWINGS

FIG. 1 is a longitudinal cross-sectional view of a tool diverter constructed according to the principles of the present invention;

30 FIG. 2 is a sectional view taken along the line 2-2 of FIG. 1; and

35 FIG. 3 is a schematic representation of a system incorporating the tool diverter of the instant invention and in which a single tool holder is utilized to direct a TFL tool into one of two well completions with fluid and gas flow controlled by external valving.

DESCRIPTION OF THE PREFERRED EMBODIMENT

40 Referring to FIG. 1 there is illustrated a tool diverter constructed according to the principles of the instant invention. Illustrated is a main diverter body 1 with an inflow pipe connection 4 secured to a cover 2 which contains outflow pipes 5 and 6. Body 1 contains a tapered bore with a cylindric bore extending toward pipe 4. A rotatable plug-type deflector body 3, secured to shaft 7, contains a conducting groove 8, running in the position shown, in extension of pipe 5, which continues through the cylindric portion of the deflector body as hole 14. Plug 3 also contains a plurality of sharp edged grooves 20 which serve the purpose of scraping mud and foreign matter from the inner surface of main diverter body 1 when body 3 is rotated.

45 Body 3 can be rotated to line up with either outflow pipe 5 or 6. The inner space of body 1 and cover 2 is held pressure tight by packing 9 located between gland 10 and shaft 7. Thrust bearings 11 and 12 acting against deflector body 3 and collar 13 absorb axial forces. The cylindric portion 15 of deflector body 3 and the shaft 7 are journaled in bores of the diverter body 1 and the cover.

50 Rotation of the body 3 may be effected by an electric or hydraulic motor or a hydraulic cylinder acting by gears or gears and rack on shaft 7 or other suitable mechanical means. The movement may be stopped by a cam on shaft 7 actuating on an electric switch or by a plunger valve and mechanical stops. Arrangements suitable for the above functions are disclosed in copending application Ser. No. 741,397, assigned to the assignee of the instant application.

55 Referring to FIG. 3, there is illustrated a system incorporating the tool diverter of FIG. 1 and designed to allow a single TFL tool contained in TFL tool holder 15 to service two well completions A and B. As illustrated, valves 12, 13 and 14 are placed each in one line leading to the diverter 11. This arrangement illustrates clearly that the flow of TFL fluid or gas will be controlled by the valves, which will prevent any inter-

connection between the systems of each of the well completions. The function of the tool diverter is, in this case, to divert the tool coming from the tool holder 15 to line 16 or 17 leading to well completion A or B respectively. The entire assemblage of tool holder 15, tool diverter 11, piping, and valving, may be contained within a pressure vessel 19 located on the sea bottom to which a plurality of wells are connected. This arrangement allows equipment which may require adjustment to be contained in a pressurized environment allowing a diver to work under atmospheric conditions.

It is to be noted that the tool diverter of the instant invention is of fairly simple construction and need not be manufactured to the extremely high tolerances required of prior art diverters. The plug-type deflector body 3, for example, need only loosely fit within the chamber of main diverter body 1, since the function of preventing interconnection between the systems of each of the well completions is controlled by external valving. Further, the configuration illustrated is particularly susceptible to inclusion in a automated system where maintenance may be effected in a predetermined and systematic manner.

While the invention has been described with respect to several physical embodiments constructed in accordance therewith, it will apparent to those skilled in the art that various modifications and improvements may be made without departing from the scope and spirit of the invention. Accordingly it is to be understood that the invention is not to be limited by the specific illustrative embodiments but only by the scope of the appended claims.

We claim:

1. A tool diverter for directing TFL tools comprising in combination:

a casing with an inflow pipe connection and a plurality of outflow pipe connections, said casing forming a bore

comprising a tapered bore portion extending toward said outflow tube connections and a cylindric bore portion extending toward said inflow tube connection;

5 a rotatable plug shaped deflector body located within said bore, said deflector body having a conducting groove positioned to connect said inflow pipe connection to a selected one of said plurality of outflow pipe connections depending upon the rotated position of said deflector body; and

a plurality of sharp edged grooves on the periphery of said plug-type deflector body, said grooves oriented substantially parallel to the axis of rotation of said deflector body so as to scrape foreign matter from the inner surface of said casing when said deflector body is rotated.

10 2. The tool diverter of claim 1 further comprising means for rotating said rotatable deflector body.

3. The tool diverter of claim 2 wherein said rotating means comprises:

a shaft connected to said deflector body; and
remotely controllable actuator means operatively connected to said shaft to rotate said shaft and rotate said deflector body.

4. The tool diverter of claim 2 further comprising means operatively connected to said inflow and outflow pipe connections for controlling the flow of material through said diverter.

5. The tool diverter of claim 1 wherein said material flow control means comprises a plurality of valves at least one of said valves in each line leading to said inflow and outflow pipe connections.

6. The tool diverter of claim 1 further characterized in that said plug-type deflector body loosely fits within said casing.
